CORPORATION OF OHIO.

COMBINATION-LOCK.

1,345,575.

Specification of Letters Patent.

Patented July 6, 1920.

Application filed February 8, 1917. Serial No. 147,437.

To all whom it may concern:

Be it known that we, WILLIAM T. BENHAM and EDGAR M. BENHAM, citizens of the United States, residing at Norwood, in the county of Hamilton and State of Ohio, have invented new and useful Improvements in Combination-Locks, of which the following is a specification.

Our invention relates to the class of locks commonly known as "combination" or "permutation" locks, having a tumbler-system adapted to be "set" or "reset" to given combinations of dial-numbers, requiring corresponding manipulations of the dial to bring the tumblers into proper relation to allow the bolt to be withdrawn; and its object is to so simplify and improve the structure and principle or mode of operation as to enlarge the range of usefulness of such locks.

As such locks are at present constituted, in order to "work" the combination and release the bolt, a somewhat complicated process of complete revolutions, or "turns," of the dial is necessary before "passing" to the specific radial point or number required at each step of the manipulation;—the number of "turns" differing at each successive step. Thus, to work a four-tumbler combination requires fourteen complete revolutions of the dial, divided unequally between the successive steps and relative forward and back motions. Not only is this a tax upon the memory but involves closest attention and takes much time. Moreover, a mis-step at any point in the manipulation requires a return to the beginning and starting afresh.

This is due to the fact that the present tumbler-system involves a series of interconnected tumblers in which the movement of the drive element or tumbler is communicated directly to the first tumbler and by the movement of the latter to the next, and so on through the series,—each tumbler being provided with a fixed "dog" or pin to engage the next in series.

In our invention, a different method or principle of action is introduced, namely: We employ unitary tumbler-disks in series, constituting the system, which are entirely independent of each other, being rotatably seated on an extended hub of the drive-tum-

bler with which each is held in frictional engagement—the drive-tumbler being removably affixed to the dial-arbor. The tumblers, being provided with radial pawls extending outwardly beyond their peripheries, are arrested by the laterally extended cross-head of the fence in the back and forth revolutions of the dial arbor and thus the radial relations of the tumblers are successively established and maintained, one by one, until the peripheral slots of all are lined up with that of the drive-tumbler, and the cross-head of the fence drops down into said slots and holds the parts rigid while a slight back turn of the dial-arbor releases the bolt.

The so-called drive-tumbler, in this instance, is removably fixed to the dial-arbor and rotates with it and does not communicate initial motion to the adjacent tumbler to be transmitted through the series as is usual. It serves only to present a smooth peripheral riding surface for the fence, a trifle higher than the toothed peripheries of the tumblers and an effective slot into which the fence drops to form a rigid non-rotative connection of all tumblers with the arbor during manipulations of the bolt. Its extended hub enables the entire tumbler-system to be held together as a unit, upon removal from the arbor, for re-setting, etc.

By this tumbler-system of construction and principle of operation, and the use of a dial numbered both ways (right and left) from a common point registering with the tumbler-slots, the turns or complete revolutions of the ordinary combination locks are entirely eliminated and the entire process of working much simplified and shortened. Moreover, a mistake at any step is corrected instantly by a simple turn to the last preceding number, and proceeding thence forward as if no error had occurred.

The construction of the lock itself is also much simplified, cheapened, and the process of resetting to new combinations facilitated.

Our invention is illustrated in the accompanying drawings, in a preferred form of structure, in which only so much of the lock mechanism is shown as is concerned with the fence, main bolt and tumbler mechanism, in which:

Figure 1 is a plan of the lock and its cas-

ing from the rear—the covering plate being removed—showing the relation of the dial-arbor, fence, and locking bolt;

5 Fig. 2, a perspective view of the operative head of the fence which extends over the tumblers;

Fig. 3, a side elevation of the dial-arbor, with the tumblers thereon—including the drive-tumbler;

10 Fig. 4, a lower face view of the drive-tumbler detached, showing details of structure;

Fig. 5, a face view of one of the tumblers detached, showing the marking in relation 15 to the peripheral teeth, and showing the pawls in place (partly in dotted lines);

Fig. 6, a face view of one of the pawls, detached, coupled with a side or edge view;

20 Fig. 7, an axial cross section of the drive-tumbler detached; and

Fig. 8, a face view of one of the non-rotating friction washers.

Referring to the drawings herewith, A designates the lock casing and, B, the lock bolt—the latter guided in the end-face of 25 the casing through which it operates and between slotted studs b, b.

The fence C, is pivotally connected to the lock bolt B, as shown, and extends rearward,—its head being laterally extended as 30 a cross bar c, resting upon the drive tumbler, D⁵, and extends across the peripheries of the system of tumblers, D. The drive tumbler is mounted on the arbor E, which 35 is journaled in a suitable bearing extending through the front wall of the casing and externally carries the dial, e¹, and knob, e², as is usual.

40 The tumblers in the present illustration are integral disks, D (numbered herein to indicate their series relation), and have toothed peripheries,—the number of teeth corresponding with the unit fractions of rotation marked upon the dial,—each disk being marked with radial markings on one face, corresponding with the dial markings. Each of said tumbler-disks, D, and the 45 drive-tumbler, D⁵, is peripherally slotted as shown at s (Figs. 4, 5). The tumblers, D, are carried loosely upon an extended hub, d, of the drive-tumbler, D⁵, and secured thereon by a spring ring, d¹, resting in a shallow circumferential groove at the end of the hub. The drive-tumbler, D⁵, is 50 threaded to engage upon corresponding threads of the arbor, E, and is held against rotation thereon by a key or spline, p, engaging in longitudinal slots in the usual manner of such connections.

60 Employed with each of said tumblers are two duplicate radial pawls, f (Fig. 6) formed of sheet metal, perforated at the larger end to ride upon the axial hub, d, of the drive-tumbler, D⁵, side by side at the rear face of each disk. The pawls project

beyond the periphery of the disk and the outer end of each is bent forward upon itself and recessed at the extreme point as shown at f¹ (Figs. 5, 6) to engage upon any tooth of the disk. Between each set of 70 pawls, f, and the contiguous face of the next disk in series is a non-rotating friction washer, w, provided with opposite projections (Fig. 8) to engage in corresponding exterior grooves of the drive-tumbler hub, d. The entire series of tumblers is held in frictional contact by the detachable spring ring, d¹, (Fig. 3) and the friction washers, w, and, therefore, normally rotate 75 with the arbor, E, and drive tumbler, D⁵. 80

The dial and the tumbler disks are radially marked and numbered right and left from a point which, in the tumblers, falls at the center of the space occupied by the peripheral slot, s,—this being a common 85 zero point from which each duplicated series of numbers starts and continues to the highest number—(say 45). The peripheral slots s, are of sufficient size to enable the operator to read the number uncovered by the slot of one tumbler upon the adjacent tumbler in rear, thus facilitating the proper radial adjustment of the tumblers in the desired series relation, so that re-setting is 90 accomplished without removal of a tumbler 95 from its group or series. The combinations are to be in successively diminishing integers.

To set the tumblers—say to the combination 40, 30, 20, 10—the pin or key, p, is 100 withdrawn and the drive tumbler, D⁵, with its hub and the tumbler series thereon, detached from the arbor, E. The tips of the pawls, f, of the first tumbler, D¹, are pushed or “sprung” rearward to disengage the teeth 105 of the tumbler-disk, and rotated to and re-engaged with the teeth designated as 40, one at each side of the slot, s. The pawls of the second tumbler, D², are in like manner engaged with the corresponding teeth, 30, at opposite sides of the same zero point; and in like manner the duplicate pawls of the remaining tumblers are “set” to their 110 respective numbers 20 and 10.

The re-setting being accomplished, the 115 drive tumbler and is tumbler system are replaced upon the arbor, E, preserving the alinement of the slots s and secured in place. The fence C is dropped into the trough formed by the alined slots of the tumblers with the bolt still unlocked, a partial rotation of the dial backward lifts the cross bar of the fence out of the slot s in the periphery of the drive tumbler and of the tumbler series. When the arbor, E, is rotated, carrying with it the tumbler system, the cross bar, c, contacts with the pawl tips one by one and arrests the rotation of each tumbler in turn, in whichever direction it is rotating. Inasmuch as the numbers se- 120 125 130

- lected for a given combination represent successive distances along the peripheries of the several tumblers from a common zero or starting point, the tumblers set to the 5 smaller numbers will first be arrested by the fence and displaced relatively backward or forward as the case may be until the slots of the tumblers set to larger numbers are brought into alinement with each other and 10 with the slot of the driving tumbler. This is true whatever be the order of the tumbler on the hub so that the number to which any tumbler is set bears no relation to its position on the hub.
- 15 The mode of operation is as follows: As a preliminary, the dial is turned in either direction through practically a complete revolution. This lines up all the pawls on one side of the zero with the fence. This 20 preliminary rotation may pass through zero and stop at the largest number of the combination, or, the rotation may be reversed and arrested at the same number on the opposite side of the zero. Either of these 25 movements brings the slots of the tumbler set at the largest number in line with the slot of the drive tumbler. The dial is then rotated in the opposite direction to the second number of the combination which alines 30 the slot of the corresponding tumbler with the slot of the drive tumbler, and so with the slot of the tumbler already set. A rotation of the dial in the first direction to the 35 appropriate number brings the third tumbler into line and successive alternate movements bring the tumblers one by one into position. As the numbers of the combination are successively smaller, the second pawls of the tumblers already set are not brought 40 into contact with the fence, so that the setting of these tumblers is not disturbed. When slots of all the tumblers are in line, the fence drops into them and the bolt may be withdrawn as usual. When the dial is 45 rotated so as to shoot the bolt, the inclined face of the fence rides on the corners and out of the slots and then, striking the pawls, disarranges the alinement of tumblers.
- Instead of peripheral teeth, a concentric 50 series of apertures in the disk may be used with projecting pins on the pawls to engage in same, but while we regard this plan as a mechanical equivalent, construction here shown is considered superior.
- 55 We claim as our invention and desire to secure by Letters Patent of the United States:
1. In a tumbler lock, in combination with a dial and its arbor, a disk-tumbler notched 60 around its periphery in correspondence with the unit markings of the dial; a radial pawl adapted to seat concentrically with and adjacent to the tumbler and adjustably engage the same and extend outwardly beyond it; and a fence adapted to extend across the 65 tumbler in the rotative path of said pawl-extension and arrest the rotation of said tumbler by contact with said extension.
2. In a combination lock of the character indicated, a dial arbor; a drive tumbler with 70 extended hub adapted to be removably affixed to said arbor; a plurality of circular disk-tumblers loosely carried upon said hub in rotative frictional engagement; radial pawls seated upon said hub,—two adjacent 75 to each disk-tumbler in adjustable but normally fixed relations and extended beyond its periphery; and a "fence" extended laterally across all of said tumblers as an arresting element contacting with said pawls. 80
3. In a tumbler lock of the character indicated, in combination with a series of unitary disk-tumblers each provided with a peripheral recess and adjustable radial pawls; a fence having a cross-head extension adapted to ride upon the peripheries of the tumblers and arrest the rotation of the tumblers by contact with the pawl-terminals and to fall into the cross groove formed by alinement of the peripheral recesses. 85 90
4. In a tumbler lock of the character indicated, the combination of a disk-tumbler having a notched periphery; a radial pawl carried concentrically adjacent to said disk extending beyond its periphery and normally engaging with its peripheral notches and adapted to be sprung out of engagement for resetting by the resiliency of the pawl shank without disturbance of other parts, and a fence extending across the tumbler adapted to arrest the rotation thereof by contact with said pawl. 95 100
5. A tumbler lock embodying in combination a dial arbor; a plurality of disk-tumblers independently seated thereon in frictional rotative engagement and marked with units of rotation in both directions from a zero point to an approximate diameter; two radial pawls concentrically seated on the arbor adjacent to each disk-tumbler and adapted to 105 engage adjustably therewith in normally fixed relations and project beyond the peripheries; and a fence arranged as an arresting abutment across and in contact with said disk-tumbler between and in the path 110 of said projecting pawls. 115
6. In a permutation lock, a tumbler system embodying a dial arbor, a drive tumbler having an extended hub removably seated on said arbor in normally fixed relations; a plurality of independent unitary circular disk tumblers seated upon said hub in frictional engagement therewith; radial pawls,—two adjacent to and adjustably connected with each disk; and friction washers 120 125 non rotatively connected with said hub, interposed between consecutive disks,—the whole being removable and replaceable as

an entity of structure in relation to the dial arbor for the convenient resetting of combinations.

7. A combination lock embodying a dial arbor; a drive tumbler removably mounted thereon; a series of independent disk-tumblers carried upon the "stump" or hub of the drive tumbler; radial pawls adapted to

be adjustably connected with the tumblers; and a fence arranged across the tumbler system in the path of the pawls as a stop, limiting the rotation of the tumblers.

In testimony whereof we have hereunto set our hands.

WILLIAM T. BENHAM.
EDGAR M. BENHAM.
